(**) Term: **14 Years**

The ornamental design for an integral floating fishing rod
handle and reel combination, as shown.

DESCRIPTION

(21) Appl. No.: **29/159,555**

FIG. 1 is a perspective view of an integral floating fishing
rod handle and reel combination showing our new design;
FIG. 2 is a right side elevational view, at a slightly enlarged
scale thereof;

(22) Filed: **Apr. 24, 2002**

FIG. 3 is a top plan view thereof;

(51) LOC (7) Cl. **22-05**

FIG. 4 is a left side elevational view thereof;

(52) U.S. Cl. **D22/138**

FIG. 5 is a bottom plan view thereof;

(58) Field of Search D22/134-144;
43/22, 23, 25

FIG. 6 is a front elevational view thereof; and,

(56) **References Cited**

FIG. 7 is a rear elevational view, at same scale as FIG. 6,
thereof.
